UNITED STATES PATENT OFFICE.

THOMAS BRABSON, OF NEWARK, NEW JERSEY.

HAME-TIP.

SPECIFICATION forming part of Letters Patent No. 352,606, dated November 16, 1886.

Application filed March 25, 1886. Serial No. 196,546. (No model.)

To all whom it may concern:

Be it known that I, THOMAS BRABSON, a citizen of the United States, residing at Newark, in the county of Essex and State of New Jersey, have invented new and useful Improvements in Hame-Tips, of which the following is a specification.

This invention has for its object to provide a hame with a spherical metallic head of novel construction, whereby such head is not liable to be indented, collapsed, or distorted, but is retained in its original smooth and unbroken shape.

The object of my invention I accomplish in the manner and by the means hereinafter described and claimed, reference being made to the accompanying drawings, in which—

Figure 1 represents a front elevation of a hame provided with my improved tip. Fig. 2 is a longitudinal central section of the tip detached, on a larger scale than the preceding figure. Fig. 3 is a similar view of a modification.

Similar letters indicate corresponding parts. In the drawings, the letter A designates the wooden body of the hame, and B is the metallic tip. The form of the tip is the same as that of the tip in common use, and it is constructed of one piece of sheet metal, as usual, with a tubular shank, a, and a hollow hemispherical head, b; but in this head b, I insert a lining, C, which fits the interior of the same and supports the material of the head at all points. This lining C is in the form of a hollow globe, or of a section of a hollow globe, as shown in Fig. 2, in which case it is made of metal; or it can be in a solid form, Fig. 3, and in this case it is made of wood or other light material which will offer sufficient resistance to indentation.

Heretofore, as in my Letters Patent dated July 31, 1883, No. 282,261, metallic hame-tips were spun or cast with a hollow globular head of thin metal; but the great disadvantage of such tips is that, owing to the necessity of having the metal very thin to prevent unnecessary weight and expense, they are very liable to be indented and distorted during the handling of the hame. This disadvantage I overcome without increasing the weight to any appreciable extent by the use of the stiffening C, which I insert in the process of spinning the tip—that is to say, the metal which forms the head is spun directly about the lining as a core and is contracted thereunder, whereby the same is caused to firmly encompass the lining, and the resisting power of the head to indentations or distortion is greatly increased.

With varying forms of head the shape of the lining is naturally changed to correspond with the form of head.

The shank and globular head being made seamless and jointless, and combined with the spheroidal lining, produces a superior hame-tip which is very desirable.

What I claim as new, and desire to secure by Letters Patent, is—

A hame-tip consisting of the spheroidal lining, and the shank and globular head made seamless and jointless, substantially as described.

In testimony whereof I have hereunto set my hand and seal in the presence of two subscribing witnesses.

THOMAS BRABSON. [L. S.]
